FIG. 7.

Shiro Higuchi
INVENTOR

UNITED STATES PATENT OFFICE

SHIRO HIGUCHI, OF LOS ANGELES, CALIFORNIA.

SANITARY TELEPHONE-TRANSMITTER COVER.

1,260,380.

Specification of Letters Patent.

Patented Mar. 26, 1918.

Application filed June 4, 1917. Serial No. 172,689.

To all whom it may concern:

Be it known that I, SHIRO HIGUCHI, a subject of the Emperor of Japan, residing at Los Angeles, in the county of Los Angeles and State of California, have invented a new and useful Sanitary Telephone-Transmitter Cover, of which the following is a specification.

This invention relates to and is designed to 10 provide a novel and useful cover or cap for telephone transmitters so that the use of the same will render the telephone more sanitary for the operator, while at the same time a greater efficiency will be secured in 15 the transmission of sound.

An object of this invention is to provide 20 a device of this character which will be inconspicuous when applied, and which is simple and of cheap construction, and which 25 can be easily and quickly secured in or removed from position.

To these ends the invention consists in certain novel and peculiar features of construction and arrangement of parts, as hereinafter described and claimed, and in order 25 that it may be fully understood reference is to be had to the accompanying drawings, in which—

Figure 1 represents in section a telephone 30 transmitter mouth-piece with a cover embodying my invention, applied thereto; Fig. 2 is a front elevation of the same; Fig. 3 is a vertical section of a modified form, showing a rubber cap or cover having a coating 35 of shellac or glue; Fig. 4 shows a modified form having a disk in the center of the cover to increase the vibration thereof; Fig. 5 is a modified form having a corrugated surface; and Fig. 6 is a modified form consisting of a plain rubber cap with reinforcing edge. Fig. 7 shows a telephone having 40 my invention applied thereto.

Referring to the drawings: The cover shown in Fig. 1, consists of a resilient disk 45 7, preferably of mica, and provided with apertures 8, and a securing and retaining flange 9, of soft elastic rubber, comprising a keeper for the cover, and having a reinforcing flange 10.

50. The modified form shown in Fig. 3, con-

sists of an elastic thin rubber cap 11, provided with apertures 12, reinforced with eyelets 13, and a coating 14, of glue or shellac upon the rubber cap.

The modified form shown in Fig. 4, consists 55 of an elastic and resilient rubber cap 15, provided with a series of reinforced apertures 16, and a vibratory disk 17, in the center thereof.

The modified form of cover shown in Fig. 60 5, consists of a corrugated resilient disk 18, having an elastic rubber keeper or securing flange 19.

The modified form shown in Fig. 6 consists 65 of a plain thin rubber cover 20, provided with the reinforcing edge 10.

In the forms shown I have provided a thin cap or disk of resilient and vibratory material, provided with reinforced apertures and other amplifying means, effective 70 for the transmission of sound waves, and further provide a means for speedy removal of the device for cleansing purposes.

In each form shown, the disk may be inscribed with advertising legends if desired. 75

The invention is obviously susceptible of modification in the mode of attachment, in the character of the vibratory means, and in the character of the sound amplifying means.

80. What is claimed is:

1. The combination with a resilient closure means having a series of apertures and a reinforcement on the edge of each aperture, of an annular elastic securing ring 85 therefor.

2. A telephone transmitter cover, comprising a rubber cap stretched over the transmitter mouth-piece, and having apertures, and eyelets in the apertures. 90

3. A telephone transmitter cover, comprising an elastic fabric tensely drawn over the mouth-piece, and a series of eyelets in the fabric.

4. In a telephone transmitter cover, the 95 combination with a tensed elastic mouth-piece closure, of a series of eyelets therein, and a vibration amplifier in the center thereof.

5. In a telephone transmitter cover, the 100

combination with resilient mouth-piece closure means, of vibratory amplifying means fixed thereto.

6. An elastic telephone transmitter closure adapted to be tensed by stretching over the mouth-piece, having a series of apertures, and eyelet reinforcements for the apertures.

7. The combination with vibratory mouth-

piece closure means, of vibratory amplifying means secured thereto.

In testimony whereof I hereunto affix my signature this 28th day of May, 1917.

SHIRO HIGUCHI.
